UNITED STATES PATENT OFFICE.

EDGAR L. LOGEE, OF PROVIDENCE, RHODE ISLAND.

DESIGN FOR A BROOCH OR SCARF-PIN.

SPECIFICATION forming part of Design No. 16,717, dated June 1, 1886.

Application filed April 13, 1886. Serial No. 198,773. Term of patent 3½ years.

To all whom it may concern:

Be it known that I, EDGAR L. LOGEE, a citizen of the United States, residing at Providence, in the county of Providence and State of Rhode Island, have invented and produced

5 a new and original Design for Brooch or Scarf-Pin, of which the following is a specification, reference being had to the accompanying drawings, forming a part thereof.

10 Figure 1 is an elevation of my said newly-designed scarf-pin, and Fig. 2 is a side view of the same, these two figures being necessary to fully illustrate the design.

15 The leading features of my design consist of a circular setting for the jewel, that represents a handle, and an ornamental shank and a hook, these three parts together presenting the general appearance of a conventionalized button-hook.

In the drawings the jewel is represented by 20 *a*, which is mounted in a fluted and grooved setting that represents the handle to a shank, *b*, ornamented with transverse grooves, and which has at the opposite end a hook, *c*. The pin *d* is on the lower side. 25

I claim—

The design for a scarf-pin, a brooch consisting of a jewel, *a*, mounted in a fluted and grooved setting, a grooved shank, *b*, and a hook, *c*, the whole representing a conventionalized button-hook, in the manner herein shown and described. 30

EDGAR L. LOGEE.
